MOTORBOAT

Ted R. Boles, Toledo, Ohio

Application May 14, 1951, Serial No. 226,264

3 Claims. (Cl. 115—26)

1

This invention relates to marine craft and the propulsion thereof.

This invention has utility when incorporated in a pair of parallel spaced cylindrical floats, more particularly as providing support and mounting for a pedal operated propeller or paddle wheel, the carrying frame for which is in conjunction with steering control.

Referring to the drawings:

Fig. 1 is a side elevation of an embodiment of the invention in a twin hull type of boat;

Fig. 2 is a view looking into the boat of Fig. 1 from the right showing the forward inter-float frame and forward rudder;

Fig. 3 is a plan view of the float or hull pair, with the rudders or steering features, as well as the paddle wheel pair, broken away from their supporting frame on the float;

Fig. 4 is a view from the line IV—IV, Fig. 1, showing the second or rear inter-float connecting arch frame;

Fig. 5 is a fragmentary enlarged plan of boat or vehicle steering control cable for one side;

Fig. 6 is a side elevation of the vertical carrying frame primarily located on the arch frames and extending aft to a rear float spacer; and

Fig. 7 is an enlarged view from the line VII—VII, Fig. 3, showing weld-anchored reinforcing pads for weld-connecting an arch frame to a float.

The floats are herein shown as comprising two light gage sheet metal cylindrical tubes or shells 1, 2, having under-pitched front ends 3 and straight back end closures 4, all normally sealed. However, in the event of seepage, the floats may be provided with removable drain plugs 5. At the aft end, a spacing angle bar 6 is weld-anchored to the crown or tops of the floats 1, 2, at the ends 4.

In order adequately to take care of the load strain on the relatively thin gage sheet metal walls of the floats 1, 2, at frame or load carrying strut regions, pads 7 have welds 8 (Fig. 7) with additional welds 8 between the pads 7 and float spacer tube 9 at the front region. Tube 9 cooperates with the angle 6 which, as at the junction of the end 4 with the float wall tops, provides substantial mounting against collapse from down load strain thereon. Additionally from the pads 7 rise a pair of co-planar arch tubes 10, 11, constituting a double arched member, with inter-arc stiffening means or spacers 12, contributing to physical strength in a light weight rigid structure, adapted, not only to bear the load strain, say of two individuals, but also to withstand buffeting of waves and windstrains.

2

The forward inter-float arch pair 10, 11, 12, has aftward slanting in upward extent a pair of weld-assembled tubes 13 as the forward support for the vertical carrying frame or chassis at a tube or steering column 14. In the event there be adopted the bicycle-built-for-two type of frame for lady and gentleman, the chassis may have a drop section 15 to a seat post column 16, with a high frame section 17 to a follower or rearwardly parallel seat post column 18. Therefrom there is trailing section 19 to inner arch tube 11 of the aft or second arch frame 10, 11, 12.

At the junction of the under portion of the frame section 15 with the column 16 is a bearing

15 20 providing mounting for a forward sprocket wheel 21 with pedal pair actuation therefor. In addition to pedals 22 at the sprocket wheel 21, pedals 22 are at a sprocket wheel 23 in the region of the lower portion of the column 18. 20 There is a brace 24 from bearing 25 for the wheel 23. The brace 24 is to the frame arch 11. The chassis has a lower rigid integral brace 26 between the bearings 20, 25, and thence aft a pair of angle sections 27 to a bearing 28 and thence to rear anchorage by welding at the spacer 6.

At the steering column 14 there is an L-top post 29, normally forwardly pitched for adjustable mounting of a handle bar 30. On the column 16 a seat 31 is adjustable for the convenience of riding of a passenger or operator of the craft using the pedals 22 at the wheel 21. For the aft or normal propulsion operator of the vehicle there is a seat 31'. Connecting the sprocket wheels 21, 23, is a sprocket chain 32. Fixed with

30 35 the wheel 23 is a sprocket wheel 33 having a chain 34 therefrom to a sprocket wheel 35 mounted in between the bearings 28 for location between the parallel angle sections 27. Outboard from the bearings 28, are paddle wheels 36, 40 having the blades of one staggered relatively to the blades of the other, in thereby balancing and distributing the power of propulsion to the water.

The steering column post 29 protrudes downwardly to a universal joint 37 to a stem 38 extending thru a bearing 40 offset aft from the spacer tube 9 (Fig. 6). As below this bearing 40 and short of below the lower plane of the floats 1, 2, there is fixed with the stem 38 a rudder 41. The stem 38, above the bearing 40, has fixed therewith and forwardly extending an arm 42 from opposite sides of which extend cables 43. At the mounting pads 7 for the spacer 9 are guide pulleys 44. In proximity to the connections for the spacer 6 with the floats 1, 2, are additional 50 55 guide rollers or pulleys 44. There is thus provided guide means from the arm 42 for one cable

43 each way therefrom to aft along the respective floats 1, 2, near the top inner side thereof, which cables 43 are connected with a block 45 centrally of a link bar 46 connecting arms 47 from bearings 48 at the ends of the spacer 6. 5 Integral with the arms 47 are down rods 49 to lower bearings 50. Fixed on each rod 49 is a wing or rudder 51.

Between the arch brace 10, 11, 12 as aft and the bearings 28 for the sprocket wheel 35 operating the paddle wheels 36, there is bracing means 52. It is to be noted that primarily the chassis is located between the floats 1, 2, by the pair of inter-float arches 10, 11, 12. Desirably, the positioning of the chassis is not only central, but the 15 seat 31 at the column 16 is about midlength of the floats 1, 2. This means that the forward ends of the floats 1, 2, will have advantageous upward deflection, if any out of level reflection occurs. Furthermore, for such program, in the 20 event there be but one individual on the vehicle, such one may use the seat 31 on the column 18, and adjust the steering column 29 to have its L-end directed aft in lieu of forwardly (see dotted lines in Fig. 6). This gives a greater 25 leverage for steering, but in so doing requires further swinging of the handle bars 30. The hands of an aft rider may grasp the chassis frame of, say, bar 17, or the body of the one riding forward.

A boat having a weight of about 260 pounds with two persons aboard it to add as much as 300 pounds more, will cause the two 12 inch diameter floats, each 10 feet long and spaced apart about 27 inches, to submerge only slightly 35 above the horizontal diameter of the floats. At this submergence all of the height of the 40 rudders 41 and 51 will be in the water. When the rudders, interconnected by the cables 43, are adjusted for straight ahead movement, that is, parallel with the axes of the floats, there is provided positive direction control to such 45 straight forward course. The rudders are so connected by cable 43 that the aft pair 51 slants oppositely from the slant of the front rudder 41 connected to the steering column 29 and handle bars 30. This means that the craft may be given such sharp turning in quiet water that it may reverse its direction in a distance of only a little over the length of the floats. The overall 50 dimensions provide stability over that of a row

or power boat. The maneuverability of this craft has an appeal to sportsmen including fishermen and anglers because of its easy and rapid operation.

What is claimed and is desired to secure by Letters Patent is:

1. A boat comprising a pair of parallel floats, at least a fore double concentric arched member connecting said floats and extending above the top of said floats, a frame fastened to the top point of said arched member, a forward rudder below said fore arched member, a handle bar pivoted on a vertical axle journaled in said fore member, said axle extending from above said fore member directly below to said forward rudder, at least one aft rudder, and means connected between said aft rudder and said forward rudder to oscillate simultaneously said forward rudder oppositely to said aft rudder.

2. A boat comprising a pair of parallel floats, fore and aft double concentric arched members, each connecting said floats and extending above the top of said floats, a frame fastened to the top points of said arched members, a forward rudder below said fore arched member, a handle bar pivoted on a vertical axle journaled in said fore member, said axle extending from above said fore member directly below to said forward rudder, separate rudders mounted on and trailing each of said floats; and means connecting between said trailing rudders and said forward rudders to oscillate simultaneously said forward rudder oppositely to both said trailing rudders.

3. A boat according to claim 2 wherein said fore member and forward rudder are located between the midpoints and forward ends of said floats.

TED R. BOLES.
